UNITED STATES PATENT OFFICE.

ARTHUR B. DAVIS, OF ELKRIDGE, ASSIGNOR TO THE VIADUCT MANUFACTURING COMPANY, OF BALTIMORE, MARYLAND.

DESIGN FOR A CALL-BOX.

SPECIFICATION forming part of Design No. 23,949, dated January 8, 1895.

Application filed May 10, 1894. Serial No. 510,806. Term of patent 7 years.

To all whom it may concern:

Be it known that I, ARTHUR B. DAVIS, a citizen of the United States, residing at Elk-

ridge, in the county of Howard and State of Maryland, have invented and produced a new and original Design for Messenger Call-Boxes, of which the following is a specification, reference being had to the accompanying drawings, forming part thereof.

10 Figure 1 is a front elevation of a messenger call box showing my design; and Fig. 2 a side elevation of the same—these two views being deemed necessary to fully illustrate my design.

15 The leading feature of my design consists of the call box having straight sides and bottom at right angles to each other, and a top represented by a half circle, the face of the box being provided with a hole through the

20 face of the box.

A secondary and subsidiary essential feature of my design consists of a backing to which the box is secured, the side edges of which backing are in parallelism with the 25 sides of the box, and terminating at top and bottom in ogee curves as clearly shown in Fig. 1.

A represents the face of the box, and B B the straight sides, and C the bottom at right angles to said sides.

30 D is the arched or curved top which I provide with a bead overhanging the face A, as most clearly shown at Fig. 2.

E is a circular hole through the face of the box and F is a rectangular opening, and at 35 the bottom edge thereof a nose G projects outwardly and is of the shape shown at Fig. 2.

K is the backing to which the call box is secured, and its sides are straight and parallel with the sides of the box, and the top and 40 bottom edges composed of inner and outer curves as clearly shown in Fig. 1.

What I claim is—

The design for call box substantially as shown and described.

45 In testimony whereof I affix my signature in presence of two witnesses.

ARTHUR B. DAVIS.
